troit, Mich., a corporation of New York

Application December 23, 1929, Serial No. 416,136

4 Claims. (Cl. 219—44)

The invention relates to electrically heated heat treating apparatus and more particularly to electrically heated cyanide pots and similar devices utilizing chrome nickel resistance units for heating purposes.

The prime object of our invention is to increase the effective life of a resistance unit when employed in such apparatus and to this end we have employed a modified design of heat treating apparatus as hereinafter more fully set forth.

It has been observed that in certain types of heat treating apparatus using chrome nickel heating elements the units have a much shorter length of life than do similar units in other types of heat treating apparatus. This is particularly true in electrically heated cyanide pots, that is, apparatus in which a molten cyanide salt is maintained in a heated condition by electric resistors.

We have discovered that in apparatus of the type above mentioned the electrical resistors may be maintained in operation for a longer length of time if means is provided for preventing certain chemical actions on the resistance elements.

We have discovered that one of the factors contributing to the failure of the heating elements is apparently the alternate oxidizing and reducing atmospheric conditions surrounding the heating elements. When the apparatus is in operation a reducing atmosphere surrounds the element by

reason of the introduction of carbon monoxide or sodium oxide into the chamber containing the resistance element by seepage through the top of the apparatus or gaseous penetration of the walls of the metallic container for the cyanide or both. The oxidizing atmosphere is caused by the oxygen of atmospheric air seeping into the heating or element chamber during the cooling or non-working periods. Because of temperature differential a slight vacuum is created in the element chamber during the heating or working periods. Cooling of the pot following a working period causes an equilibrium condition with the consequent infiltration of atmospheric air.

The primary cause of element failure may be attributed to this cyclic change of atmospheres. The reducing atmosphere reduces the oxide scale which covers the element surfaces. This scale, upon reduction, does not recombine with the metal of the elements but scales or sloughs off. Subsequent cooling and creation of an oxidizing atmosphere causes a fresh oxide coating to form which in due turn is reduced and lost. This cycle tends to eventually reduce the cross section area of the element and causes "hot spots" and burning with consequent failure.

To overcome the objectionable conditions as outlined above, we have designed a heat treating apparatus in which means is provided for maintaining around the heating element an atmosphere which does not alternate from oxidizing to reducing characteristics. Since it is easier to maintain an oxidizing atmosphere than a reducing atmosphere, the preferred embodiment of our invention consists in a construction designed to permit ventilation of atmospheric air around the resistor at all times.

We have also discovered that when the temperature of a chrome nickel heating element is above 1700° F., the reaction between a reducing atmosphere and the oxide scale on the heating element is greatly accelerated and we therefore find it preferable to design the apparatus so that the temperature of the heating element is not above 1700° F. under operating conditions. This may be carried out by providing sufficient area of the heating element to permit maintaining the proper bath temperature without exceeding the desired element temperature.

Our invention may be embodied in various constructions, one of which is illustrated in the accompanying drawing, wherein

Figure 1 is a sectional elevation of the apparatus;

Figure 2 is a sectional plan view thereof.

In the drawing, the apparatus consists of a base 10 and a tubular refractory lining 11 extending upwardly therefrom. The lining preferably consists of a series of refractory rings 12, each containing inwardly projecting annular flanges 13 forming recesses 14 therebetween. At the top of the apparatus there is an inwardly projecting refractory ring 15. Surrounding the lining 11 is an outer metallic casing 16 which supports a cover 17 arranged over the top refractory ring 15. A plate 18 is supported by the cover and the top refractory ring and in turn supports the bath container 19. This container is preferably in the form of a cast metal pot extending within the lining 11 and having a top annular flange 20 supported on the plate 18. The arrangement is such that the bath container 19 may be readily removed from the furnace and replaced either by a pot of the same size or in some cases by another of greater depth. Within the base 10 there is arranged a tubular conduit 21 forming a drain for the interior of the furnace, one of the functions of this drain being to remove the molten material from the furnace in case of breakage of the bath container while the furnace is in operation. The

construction, as thus far described, is similar to conventional apparatus as used prior to the instant invention, except that our improved device has a greater space between the pot 19 and the outer refractory lining 11 than is the customary practice.

In order to provide means for maintaining a substantially constant condition of oxidation or reduction within the interior of the apparatus, we provide the apparatus with means for insuring adequate ventilation of the same during the heating periods. For this purpose we make use of the drain 21 allowing air to enter the apparatus through the drain. At the top 22 of the drain there is preferably arranged a baffle 23 in the form of an inverted truncated cone having downwardly extending sides 24. These sides serve to deflect the air downwardly and outwardly thereby causing the air to come in contact with the refractory lining 11. To complete the natural draft of the apparatus, a series of openings is provided in the upper part of the furnace and as shown, the top refractory ring 15 is provided with a series of radial passageways 25 from which the tubes 26 project and lead into an annular header duct. This duct is arranged within the outer casing 16 and communicates with the outside atmosphere by means of a flue passage 28.

The heating elements are preferably arranged within the recesses 14 and as shown they are represented by the numeral 29. The terminals from the heating elements lead outwardly through the tubes 30 and 31 extending from the refractory lining 11 to a point outside of the outer casing 16.

The effect of the ventilating arrangement in the apparatus as above described is to cause a continual change of atmosphere within the refractory lining, thereby preventing the formation of alternate oxidizing and reducing conditions in the practical operation of the furnace. Since the ventilation is caused by introduction of air into proximity to the electrical resistor, our apparatus maintains oxidizing conditions surrounding the heating element both when the furnace is being heated and when it is not being heated but since the chrome nickel heating material is capable of standing up for long periods of time under ordinary atmospheric conditions at incandescent temperatures, it has been found that the ventilation of the furnace does not cause any further oxidation or deterioration of the element but on the contrary it actually prolongs

the life of the element. Further it has been found that the continual addition of fresh air while it causes a certain heat loss due to the convecting currents, nevertheless more than makes up for this loss in the added heating efficiency due to the presence of fresh air instead of the partial vacuum which heretofore existed in the older furnace types.

What we claim as our invention is:

1. A heating apparatus comprising a metallic container for molten cyanide, a refractory lining surrounding said container, electrical heating means between said container and said lining and means for circulating air through said lining to prevent deterioration of said electrical heating means by chemical action of the molten cyanide.

2. A heating apparatus comprising a base, a refractory cylindrical lining extending upwardly from said base, an electrical resistor associated with said refractory lining, a metal pot within said lining, passageways at the upper end of the apparatus permitting the escape of air from said lining, an inclined duct within said base and a baffle for directing the air from said inclined duct.

3. In a heating apparatus comprising an outer casing, an annular refractory lining within said casing, an electrical resistor within said lining, a metallic container within said lining, means for introducing air into the space between said lining and said container, a series of radial passageways at the top of said refractory lining communicating with the interior of said lining, an annular duct connected to said radial passageways and arranged between the refractory lining and said outer casing and a vent extending through said outer casing from said annular duct.

4. A heating apparatus comprising a metallic container for a cyanide compound, a casing surrounding said container, a metallic resistor within said casing and spaced from said container, said resistor being adapted to be electrically heated to incandescence thereby melting said cyanide compound through radiation and means for circulating an oxidizing gas into contact with said resistor to prevent deterioration of said resistor due to the chemical action on the metal of said resistor by said cyanide compound.
